UNITED STATES PATENT OFFICE.

RENSSELAER REYNOLDS AND GORDON B. REYNOLDS, OF STOCKPORT, NEW YORK.

BRAKE FOR POWER-LOOMS.

Specification of Letters Patent No. 24,488, dated June 21, 1859.

To all whom it may concern:

Be it known that we, RENSSELAER REYNOLDS and GORDON B. REYNOLDS, both of Stockport, in the county of Columbia and State of New York, have invented a new and Improved Mode of Applying Brakes to Power-Looms; and we do hereby declare that the following is a full, clear, and exact description of the same, reference being had 10 to the accompanying drawings, forming part of this specification, in which—

Figure 1, is a side view of part of the framing of a loom, its driving gears, and brake, and the mechanism for operating the 15 brake. Fig. 2, is a back view of the same, and Fig. 3, a top view of the same.

Similar letters of reference indicate corresponding parts in the several figures.

Our invention consists in so applying and 20 arranging the brake to act upon both the crank and cam shaft of a power loom whereby after having stopped the loom, it is made to prevent effectually any recoil, and yet is prevented binding upon the surfaces upon 25 which it produces friction and thereby interfering with the starting of the loom.

To enable others skilled in the art to make and use our invention we will proceed to describe its construction and operation.

30 A, is one of the side frames of the loom. B, is the crank shaft; and C, the cam shaft.

D, is the smaller gear on the crank shaft and E, the larger gear on the cam shaft, 35 each made with a projecting rim a, on its outer side for the brake to act upon.

F, is the brake having two faces d, e, of 40 curved form corresponding with the outer peripheral surface of the rim a, a, of the two gears, as shown in Fig. 1, the face d, to act upon the smaller gear D, and the face e, on the larger gear E. This brake is fitted to swing on fixed pin b, which is secured in 45 the frame A, with its axis parallel with the shafts, C. The pin b, which constitutes the center of motion of the brake is so arranged relatively to the centers of the shafts B and C, and the hole in the brake which fits to the said pin so arranged relatively to the 50 faces d, e, that the face e, comes into action nearer to a position directly between the centers b, B, than the face d, does to a position directly between the centers b, C, which gives the face d, an advantage over 55 the face e, in their respective operations, the

importance of which will be presently explained.

G, is the protector lever attached in the usual manner by a fulcrum pin c, to the breast beam H, of the loom.

f, is the rod connected with the outer extremity of the protector lever and passing through the arm e, of the brake in front of which the said rod has upon it a nut g, which is adjustable on a screw thread cut 65 on the said rod.

The operation of the brake is as follows:— When the shuttle fails to box, by being stopped in its passage through the web or thrown out by some obstacle, the protector 70 pin, striking the inner end of the protector lever in the usual manner and driving it toward the breast beam causes the outer end of the said lever to be moved toward the gear and thus by its nut g, to force back 75 the arm e, of the brake and bring the faces d, e, into operation on the rims a, a, of the two gears D, E, simultaneously, thus instantly stopping the revolution of the gears in the direction of the respective arrows 80 shown upon them in Fig. 1, and so stopping the loom in its forward movement without any concussion of the teeth of the gears.

When the loom is stopped the lay has generally a tendency to recoil and so carry back 85 the gears in the opposite direction but this is prevented by the arrangement of the brake as before described so that its face d, has an advantage over the face e, in their respective operations; for as soon as the 90

gears have any tendency to turn in the reverse direction the friction of the gear D, upon the face d, tends to move the brake in a direction to increase its pressure on both the rims a, a, and thus prevents the smash 95 which the recoil is so likely to produce. The above advantage also secures the infallible disengagement of the brake when the loom is started again for when the gear D, is rotating in the forward direction in 100 contact with the face d, its friction always tends to throw the brake out of operation, and when the brake is relieved of the pressure of the protector lever there is no means of counteracting this tendency. It is obvious that instead of applying the brake to projecting rims a, a, on the gears, it can be applied in an equivalent manner to act on 105 wheels specially provided on the shafts for the purpose.

What we claim as our invention and desire to secure by Letters Patent, is,

5 Applying and arranging the two faces of the brake relatively to its center of motion, and the said center of motion relatively to the centers of the crank and cam shafts in the manner substantially as described, whereby the brake is not only rendered automatic in case of recoil after the stoppage

of the loom by the action of the protector, 10 but self liberating, when the loom is started again as herein fully set forth.
